UNITED STATES PATENT OFFICE.

GEORGE A. WEBER, OF NEW ALBANY, INDIANA.

ILLUMINATING ATTACHMENT FOR SPRAY GUNS.

Application filed February 18, 1927. Serial No. 169,319.

This invention relates to an improved spray gun, such as is used in paint spraying in furniture, automobile factories, enameling plants, and similar places.

The improvement on the gun is directed to a lamp attachment which is associated with the gun in such a manner as to project a light beam on the object being treated, whereby to enable the operator to clearly observe the surface being treated, especially in dark places wherein the room artificial lighting system is insufficient to render such surfaces clearly visible for efficient coating.

What I aim to do, is to provide an exceptionally simple and inexpensive electric lamp enclosed in a housing which is especially constructed to permit it to be attached to a conventional form of paint spray gun without requiring alterations of the stock parts of the gun.

The lamp attachment is characterized by exceptional simplicity, inexpensiveness of manufacture, efficiency in construction, ease in attachment and removal, and durability.

An important factor to be considered in the construction of the novelty is the arrangement of the light or lamp casing alongside of the paint conducting barrel of the gun in order to take advantage of the heat radiating from the light for heating the paint as it passes through the barrel to cause it to flow freely.

Other features and advantages of the invention will become apparent from the following description and drawings.

In the accompanying drawings forming a part of this application, and in which like numerals are employed to designate like parts throughout the same:

Figure 1 is a side elevation of the conventional gun showing the lamp attached to one side of the barrel thereof.

Fig. 2 is a rear end elevation of the same.

Fig. 3 is a top plan view.

Fig. 4 is an enlarged longitudinal section through the attachment per se.

Fig. 5 is a cross section on the line 5-5 of Fig. 4, looking from left to right.

Fig. 6 is a fragmentary perspective view showing the light casing and lens retaining rim, with the pin and bayonet slot connection.

The gun represented in the drawings, is of conventional construction, being of the type A De Vilbiss construction. It includes handle 1, paint barrel 2, air hose connec-

tion 3, fluid hose connection 4, universal air cap and nozzle head 5, together with fluid needle adjusting screw 6 and handle retaining nut 7. Incidentally, the handle in this case is provided with a sleeve at its top which fits over the adjacent end of the barrel and is held in place by the nut 7.

I mention this because the attachment, which is generally designated by the reference character 8, is closely associated with these details. The attachment as is better shown in Fig. 4, comprises a cylinder 9, a light bulb 10 located therein, a socket 11, a switch chain 12, and support and connecting member 13. The latter is provided with a circular base 14 which is riveted to the closed end of the cylinder. The opposite end of the cylinder is provided with an inturned flange, and the lens 15 is held against this by a removable retaining rim 16.

Incidentally, the cylinder is provided with a bayonet slot 17 as shown in Fig. 6 and the lens retaining rim is provided with a pin 18 which fits into this slot and holds the lens in place. The electricity conductor is represented by the reference character 19. In this connection, it will be noticed that a suitable retaining member 20 is provided at this end of the cylinder and serves to hold an attaching disk 21 in place. This disk is provided with an arm 22 terminating in a connecting ring 23. As shown better in Fig. 3, this connecting ring 23 is arranged between the sleeve 24 on the upper end of the handle 1, and the retaining nut 7.

These details are existing ones on the ordinary gun and I take advantage of this because the attachment therefore requires no alterations of the stock parts. While considering this figure, it will be noticed that the length of the device is slightly less than the length of the adjacent portion of the gun, and that the lens terminates inwardly spaced relation to the spray head, or nozzle. Moreover, the lamp cylinder is in metallic contact with the gun barrel and as before stated, it is important to note that this brings about a new co-action of parts in that the light has the additional function of heating the paint as it passes through the barrel, thus causing it to flow freely. This is a point of novelty to be emphasized.

It is plain to be seen that with this construction the operator can coat the surface treated in a more efficient manner due to the fact that the beam of light from the lamp

will be projected onto the surface and will render it clearly visible under all conditions.

It is believed that the construction, and use, and advantages of the invention will be 5 clear to persons familiar with guns of this character. Therefore, a more lengthy description is thought unnecessary.

While the preferred embodiment of the invention has been shown and described, it 10 is to be understood that minor changes coming within the field of invention claimed may be resorted to if desired.

Having thus described my invention, what I claim as new is:—

15 As a new product of manufacture, a lamp attachment for paint spray guns comprising a cylinder closed at one end and having an inturned flange at its opposite open end, a

lamp socket in the cylinder, a lamp carried by said socket, a connecting stem carried 20 by the socket and including a circular base fastened to the closed end of the cylinder, switch operating means carried by the lamp socket, a source of current supply associated with said socket, a lens bearing 25 against said inturned flange, a retaining rim for the lens detachably connected with the cylinder, a disk bearing against the outer surface of the closed end of the cylinder and having a central opening, having an arm 30 extending from one side, and an attaching ring carried by the outer end of the arm.

In testimony whereof I affix my signature.

GEORGE A. WEBER.
